UNITED STATES PATENT OFFICE.

GOTTHILF ANSGARIUS BETULANDER, OF SODERTORNS VILLASTAD, AND NILS GUNNAR PALMGREN, OF STOCKHOLM, SWEDEN, ASSIGNORS TO THE RELAY AUTOMATIC TELEPHONE COMPANY LIMITED, OF LONDON, ENGLAND.

SEMITAUTOMATIC TELEPHONE SYSTEM.

Application filed February 22, 1921. Serial No. 446,990.

To all whom it may concern:

Be it known that GOTTHILF ANSGARIUS BETULANDER and NILS GUNNAR PALMGREN, subjects of the King of Sweden, and residents of Sodertorns Villastad, Sweden, and Varvsgatan 14, Stockholm, Sweden, have invented a new and useful Improvement in Semiautomatic Telephone Systems (for which we have filed an application in Sweden, February 11th, 1920, filed in the name of Gotthilf Ansgarius Betulander), of which the following is a specification.

This invention relates to automatic or semiautomatic telephone systems of the kind wherein the group- and line selectors are actuated by means of impulse signals according to a code system selected arbitrarily, for instance current impulses sent in various combinations over two or more line branches, alternating current impulses of different frequencies, or the like. Such switching systems have an advantage over the common systems in which the selectors are actuated by means of series of impulses, in that the speed of operation can be considerably increased, simultaneously as the inconveniences connected with the sending of current impulses in rapid succession are entirely avoided. The present invention relates to a switching arrangement adapted to regulate the sending of impulse signals according to the first-mentioned system by the control of a number switch provided at the station, by means of which the desired number is marked electrically. In full automatic systems, a number switch of this kind may for instance consist of a register adapted to be actuated from the subscriber's station, and adjusted in accordance with the desired number, whereas in semi-automatic systems, the same consists of a key board. The invention is principally characterized by the sending of the different impulse signals being controlled by a number of code relays actuating a number of contact groups located in the impulse circuit and corresponding to the different digits of the number system employed, the circuits of said code relays being in turn controlled partly by the said number switch, and partly by a sequence switch which regulates the actuating of the said code relays in the proper succession in such a manner that the impulse signals corresponding to the differ-

ent digits of the subscriber's number are sent out in proper order, according as the switching progresses.

The invention will be explained more fully hereinbelow, with reference to the accompanying drawings which illustrate the invention as applied to a semi-automatic telephone system in which the connections are established only by means of relays.

Fig. 1 shows the arrangements at the operator's position. KS denotes the key board, KM₀—KM₅ the electro-magnets by means of which the keys are retained in their depressed position, CR₀—CR₉ the various code relays, and FS the sequence switch which in the example shown comprises a number of switching relays FR₁—FR₆ and an impulse relay IR. HS designates an auxiliary switch comprising a number of shifting relays OR₁—OR₆ and a cut-off relay UR, the said auxiliary switch controlling the sending of the different current impulses. TT is the operator's telephone apparatus which is connected to a speaking key EO.

Figs. 2 and 3 show the arrangement in a group switching section. The incoming trunk lines FL are connected over link lines ML to the trunk lines GL going to the next switching section, by means of switching devices of the kind described in our Swedish Patent No. 49,816, dated April 2, 1919, patent application No. 1517/1919/. The connections between the lines FL and ML are thus established by means of a number of connecting relays A₁R corresponding to the various trunk lines FL, and by a number of marking relays M₁R corresponding to the various link lines ML, by energizing the relays corresponding to the lines that are to be connected with one another. The marking relay M₁R then effects such a mechanical marking of the series of contact groups K₁G corresponding to the link line belonging thereto that, on the connecting relay A₁R immediately after being brought in operation, only the contact group capable of effecting the desired connection will be actuated. This contact group then remains actuated as long as the connecting relay A₁R is energized, notwithstanding the fact that the marking relay is immediately de-energized on the marking being completed. In like manner the connections are estab-

lished between the link lines ML and the outgoing lines GL by means of a number of connecting relays A₂R corresponding to the various link lines, and by a number of marking relays corresponding to the different outgoing lines.

The outgoing trunk lines GL are divided in a common manner in a number of numerical groups which may be selected by means of a group selector GV which is common to a plurality of incoming trunk lines FL, the said group selector GV comprising a number of combination relays SR₁—SR₆ and a control relay HR₁. The testing of the various outgoing trunk lines belonging to the selected group is effected by means of a testing device PS comprising a number of switching relays KR₁—KR₅ and two test relays PR₁ and PR₂. This testing device is so arranged as to test the various lines in pairs, in that the different switching relays switch different pairs of test wires PL successively to the two test relays PR₁ and PR₂, the test relay which is switched to a disengaged line attracting its armature and stopping the switching operation.

According to the code system used in the present case, each digit is denoted by an impulse combination comprising two combination impulses sent out successively over the two speaking line branches *a*, *b* according to the following scheme:—

35	Digit	First impulse	Second impulse
40	0	a	a
	1	a	b
	2	a	a, b
	3	b	a
	4	b	b
	5	b	a, b
	6	a, b	a
	7	a, b	b
	8	a, b	a, b
	9	a, b	-----

The switching operation is as follows. On connecting a calling subscriber's line to a trunk line FL₁, a relay LR is brought in action, the said relay starting an operator's searcher not shown herein. On the searcher finding a disengaged operator's position, a connecting relay DR is actuated, whereby the trunk line FL₁ is connected to the telephone apparatus TT of the operator. At the same time the relay DR switches itself into a holding circuit 10, whereupon the searcher is released. On the relay DR attracting its armature, a circuit 11 is closed through a relay BR₁, which then attracts its armature and closes a circuit 12 through a relay BR₂, which in turn closes a circuit 13 through the holding electromagnets KM of the key board. The relay BR₁ lights a call lamp ARL indicating that a call has been received at the operator's position. Now the telephone operator receives the desired number and depresses the corresponding keys, where-

upon the operator actuates a starting key SK so as to close a circuit 14 through a relay TR, and a relay NR₁, which are both brought into operation. On the first-mentioned relay attracting its armature, the same switches itself into a holding circuit over a relay BR₃ which attracts its armature and cuts out the starting key. On the relay NR₁ attracting its armature a circuit 15 is closed through the selector-connecting relay V₁R₁ belonging to the trunk line FL₁, whereby the two speaking line branches of the trunk line are connected to the group selector GV. At the same time the relay V₁R₁ closes the circuit of relay ER₁ which in turn closes a circuit 16 through the control relay HR₁ of the group selector, and also a circuit 17 through a cut-off relay ER₂ which separates the battery from the remaining selector-connecting relays and thus prevents a plurality of trunk lines from being simultaneously connected to the group selector. The relay V₁R₁, however, remains current carrying over the contact 18.

When the relay BR₃, Fig. 1, attracted its armature, a circuit 19 was closed, which circuit will contain the first code relay CR₀ and the relay FR₁ of the sequence switch FS, if it be assumed that the first digit of the desired subscriber's number is 0. Now the code relay CR₀ closes the circuit 20 for the first switching impulse, which current impulse passes over the line branch *a* and energizes partly the relay OR₁ of the auxiliary switch FS, Fig. 1, and partly the combination relay SR of the group selector. The first-mentioned relay then locks itself over its contact 21. At its contact 22 the latter relay switches in the relay SR₁, which is slow to release and so indicated on the drawings by the rectangle placed between the winding and the armature, as shown in Fig. 3, which relay closes a circuit 23 through the relay SR₅, the last-mentioned relay locking itself over its contact 24 and closing a circuit 25, whereby the relay HR₁ will be short-circuited. On account of this the relay HR₁ releases its armature, thus breaking the switching impulse at its contact 26 and simultaneously closing a circuit 27 through the relay SR₄ which at its contact 28 interrupts the short circuit of the relay HR₁ so that this latter again attracts its armature. Prior to this, the relay SR₄ has locked itself over its contact 29.

On interrupting the first switching impulse, the relay OR₁, Fig. 1, releases its armature. Prior to this, however, the relay OR₂ was energized in a circuit 30. When the relay OR₁ now releases its armature, the relay OR₂ is still retained energized over a current path 31 containing the shifting relay OR₆ which short-circuited as long as the relay OR₁ was current carrying, but which is now brought in operation so as to close

- the circuit 32 for the other switching impulse, the said current path 32 containing the shifting relay OR_3 , and also the combination relay SR_2 in the group selector, Fig. 3. The last-mentioned relay now closes a circuit 33 through a relay G_0R and the marking relay M_2R_1 . The relay G_0R switches all test wires for the lines G_0L in the group thus selected to the testing device 10 PS which is started by the marking relay M_2R_1 closing a circuit 34 through the first switching relay KR_1 in the testing device. If it is assumed that the first two lines are engaged, the next switching relay KR_2 will 15 be immediately energized over the current path 35, whereby the next pair of test wires are switched to the test relays PR_1 and PR_2 . If it is assumed that the third trunk line G_0L_3 is disengaged, the test relay PR_1 is 20 now energized in a current path 36 containing the working winding AL of the test relay PR_1 . A contact 37 in the circuit of the switching relays KR is then broken so as to stop the switching operation. At the 25 same time a circuit 38 is closed through the holding winding HL of the test relay PR_1 , the operating winding of the connecting relay A_2R_3 and the marking relay M_1R_3 . The relay A_2R_3 attracts its armature and 30 connects the link line ML_3 to the outgoing trunk line G_0L_3 over the group of contacts K_2G_{31} . At the same time the marking relay M_1R_3 closes a circuit 39 for the connecting relay A_1R_1 which attracts its armature so as 35 to connect the trunk line FL_1 to the link line ML_3 over the group of contacts K_1G_{13} , whereby the connection is completed till the next switching section in which the trunk line G_0L_3 is immediately connected to the 40 corresponding group selector through the selector-connecting relay V_2R_3 contained in the circuit 39. The connecting relay A_1R_1 breaks the circuit of the selector-connecting relay V_1R_1 , whereby the group selector GV 45 is cut out. The second switching impulse is then interrupted at the contact 40, and at the same time the circuit of the relay ER_1 is broken at the contact 41, whereby all relays of the group selector are rendered currentless. The battery having again been 50 connected to the selector-connecting relays V_1R by the deenergizing of the relay ER_2 , which is slow to release as indicated by the rectangle shown in Fig. 2, the group selector 55 is in readiness for receiving a new call. When the second switching impulse was interrupted, the relay OR_3 , Fig. 1, was deenergized. Prior to this, however, the relay OR_4 was energized over a current path 42, 60 the said relay having thus locked itself over its contact 43. When the relay OR_3 is now releasing its armature, a circuit 44 is consequently closed through the impulse relay IR which again closes a circuit 45 through 65 the second relay FR_1 of the sequence switch and, assuming the second digit of the subscriber's number to be 1, through the code relay CR_1 . At the same time, however, a circuit 46 is closed through the cut-off relay UR , whereby all the relays of the auxiliary switch and the impulse relay IR are rendered currentless. The latter relay then again breaks the circuit of the relay UR at the contacts 47, whereby the relay FR_1 is rendered currentless, whereas the relay FR_2 70 is still energized over a contact 48. The second group selector is now actuated by two combination impulses sent out in succession, in the same way as the first group selector, whereupon the connection is 75 extended to a third group selector which, on the sequence switch FS having been actuated once more by the impulse relay IR , is actuated in like manner by means of two combination impulses corresponding to the 80 third digit of the subscriber's number. In this manner the switching progresses by successively switching in a new row of keys until the switching operation has been completed, when a current path 49, Fig. 1, is 85 closed through the relay BR_4 cutting off the relays BR_2 and BR_3 and breaking the circuit of the relay TR_1 and NR_1 . The latter relay then breaks the circuit of the operator's connecting relay DR . Thus the 90 operator's position is entirely separated from the trunk line FL_1 , and all relays belonging to the operator's position are rendered currentless. The connection is then 95 maintained over the above-mentioned current path 39, the latter having been extended through the connecting relays of the various switching sections, according to the progression of the switching operation. 100
- What we claim as new and desire to secure by Letters Patent of the United States is:—
1. A switching arrangement for automatic or semi-automatic telephone plants designed to operate on a code system comprising, group and line selectors, means for sending out impulse combinations and actuating a number of contact groups in the impulse circuit corresponding to the various digits of the number system employed, a number switch for partly controlling the circuits of said means, and a sequence switch for partly controlling and regulating the actuation of the said means in proper succession so that the impulse signals corresponding to the different digits of the subscriber's number are sent out in due order as the switch operation progresses. 110
  2. A switching arrangement for automatic or semi-automatic telephone plants designed to operate on a code system comprising, group and line selectors, a number of code relays for sending out impulse combinations and actuating a number of contact groups in the impulse circuit corre- 115
  3. A switching arrangement for automatic or semi-automatic telephone plants designed to operate on a code system comprising, group and line selectors, means for sending out impulse combinations and actuating a number of contact groups in the impulse circuit corre- 120
  4. A switching arrangement for automatic or semi-automatic telephone plants designed to operate on a code system comprising, group and line selectors, a number of code relays for sending out impulse combinations and actuating a number of contact groups in the impulse circuit corre- 125
  5. A switching arrangement for automatic or semi-automatic telephone plants designed to operate on a code system comprising, group and line selectors, means for sending out impulse combinations and actuating a number of contact groups in the impulse circuit corre- 130

sponding to the various digits of the number system employed, a number switch for partly controlling the circuits of the said relays having the numbers electrically marked thereon, and a sequence switch for partly controlling and regulating the actuation of the code relays in proper succession so that the impulse signals corresponding to the different digits of the subscriber's number are sent out in due order as the switch operation progresses.

3. A switching arrangement for automatic or semi-automatic telephone plants designed to operate on a code system comprising, group and line selectors, means for sending out impulse combinations and actuating a number of contact groups in the impulse circuit corresponding to the various digits of the number system employed, a key board for partly controlling the circuits of said means, and a sequence switch for partly controlling and regulating the actuation of the means in proper succession so that the impulse signals corresponding to the different digits of the subscriber's number are sent out in due order as the switch operation progresses.

4. A switching arrangement for automatic or semi-automatic telephone plants designed to operate on a code system comprising, group and line selectors, a number of code relays for sending out impulses and actuating said selectors and actuating a number of contact groups in the impulse circuit corresponding to the various digits of the impulse system employed, a key board for partly controlling the circuits of the said relays having the numbers electrically marked thereon, and a sequence switch for partly controlling and regulating the actuation of the code relays in proper succession so that the impulse signals corresponding to the different digits of the subscriber's number are sent out in due order as the switch operation progresses.

5. A switching arrangement for automatic or semi-automatic telephone plants designed to operate on a code system comprising, group and line selectors, a key board including contacts, a sequence switch also including contacts, a number of code relays corresponding to the various digits in the number system employed and controlling the impulse signals and actuating the number of contact groups in the impulse circuit corresponding to the various digits in the number system employed, each code relay being adapted to be connected for contacts on the key board to any of a number of contacts in the sequence switch, said contacts corresponding to the various digits of the subscriber's number, and said sequence switch being adapted to successively actuate said contacts.

6. A switching arrangement for auto-

matic or semi-automatic telephone plants designed to operate on a code system comprising, group and line selectors, a key board, a sequence switch, a number of code relays corresponding to the various digits of the number system employed and controlling impulse signals and actuating a number of contact groups in the impulse circuit corresponding to the various digits in the number system employed, and an auxiliary switch for partly regulating the code relays and for actuating the sequence switch.

7. A switching arrangement for automatic or semi-automatic telephone plants designed to operate on a code system comprising, group and line selectors, a key board, a sequence switch adapted successively to switch into operation the keys of said key board so that impulses may be sent in due order, a number of code relays corresponding to the various digits of the number system employed and controlling the impulse signals and actuating a number of contact groups in the impulse circuit corresponding to the various digits in the number system employed, and an auxiliary switch for partly regulating the code relays and for actuating the sequence switch.

8. A switching arrangement for automatic or semi-automatic telephone plants designed to operate on a code system comprising, group and line selectors, a key board including contacts, a sequence switch also including contacts, a number of code relays corresponding to the various digits in the number system employed and controlling impulse signals and actuating the number of contact groups in the impulse circuit corresponding to the various digits in the number system employed, each code signal comprising two impulse combinations adapted to be sent out one after the other, each code relay actuating two groups of contacts corresponding to the two impulse combinations, and an auxiliary switch for regulating the successive sending of the combination impulses and controlling said groups of contacts.

9. A switching arrangement for automatic or semi-automatic telephone plants designed to operate on a code system comprising, group and line selectors, a key board including contacts, a sequence switch also including contacts, a number of code relays corresponding to the various digits in the number system employed and controlling impulse signals and actuating the number of contact groups in the impulse circuit corresponding to the various digits in the number system employed, each code signal comprising two impulse combinations adapted to be sent out one after the other, each code relay actuating two groups of contacts corresponding to the two impulse combinations, and an auxiliary switch for

- regulating the successive sending of the combination impulses and controlling said groups of contacts, said auxiliary switch being controlled by the group and line selectors, and having means whereby the breaking of the current in the impulse circuit will shift the auxiliary switch.
10. A switching arrangement for automatic or semi-automatic telephone plants designed to operate on a code system comprising, group and line selectors, a key board including contacts, a sequence switch also including contacts, a number of code relays corresponding to the various digits in the number system employed and controlling impulse signals and actuating the number of contact groups in the impulse circuit corresponding to the various digits in the number system employed, each code signal comprising two impulse combinations adapted to be sent out one after the other, each code re-
- lay actuating two groups of contacts corresponding to the two impulse combinations, and an auxiliary switch for regulating the successive sending of the combination impulses and controlling said groups of contacts, said auxiliary switch being controlled by the group and line selectors, and having means whereby the breaking of the current in the impulse circuit will shift the auxiliary switch, said auxiliary switch also being adapted to actuate the sequence switch to advance it to another position after sending two combination impulses.
15. In witness whereof we have hereunto set our hands in the presence of two witnesses.
